UNITED STATES PATENT OFFICE.

B. FRANK TEAL, OF PHILADELPHIA, PENNSYLVANIA.

FREIGHT-CAR DOOR.

SPECIFICATION forming part of Letters Patent No. 276,644, dated May 1, 1883.

Application filed May 11, 1882. (No model.)

To all whom it may concern:

Be it known that I, B. FRANK TEAL, a citizen of the United States, and a resident of the city of Philadelphia, in the county of Philadelphia and State of Pennsylvania, have invented certain new and useful Improvements in Freight-Cars, of which the following is a specification.

My invention relates to that class of cars termed "box-cars," adapted to carry grain and other freight; and it consists in the peculiar construction and arrangement of parts, as fully described hereinafter, whereby certain defects in said cars of the ordinary construction are overcome.

In the drawings, Figure 1 is a transverse section of the car, looking toward one of the ends. Fig. 2 is the same, the doors open; Fig. 3, a transverse section on the line 1 2, Fig. 1; and Fig. 4 is a section on the line 3 4, Fig. 1.

The frame and platform A, sides B B, top C, and side door, D, are constructed in the ordinary manner; but the end, instead of being solidly closed, as is generally the case, is open at one side and provided with an end door, E, hinged or sliding in guides a a, as shown, and closing an opening extending to the floor.

By the addition of the end door it is possible to introduce into the car many articles—as rails and long timber—for the transportation of which box-cars could not otherwise be used. Heretofore it has been necessary to employ on all railroads large numbers of platform-cars, even when there is an abundance of idle box-cars. Attempts have been made to secure these advantages by providing the box-cars with end doors; but the constructions have been such as to necessitate the locking of the end doors by devices outside of and accessible from the end platforms, so that they could be tampered with during the running of the train. This also requires a double set of locks and seals and extra attention in sealing; and such cars, as heretofore made, have always been incapable of use for carrying grain. For these reasons such cars have not answered the desired purpose, and have found but little place upon the roads. I have overcome these difficulties by providing each end door with an inside self-locking device, so that but one lock and seal is required on each car. As said locks are, as usual, at the side of the car, the same

cannot be tampered with when the train is running, nor readily reached when the train is at rest. There being no exposed end lock, the end is practically as securely closed as an ordinary solid-end box-car, and there is as little opportunity of tampering with the contents.

A cheap and secure inside fastening consists of a bar, b, pivoted to the inside of the door, near the outer edge, by a bolt, c, and of about the same length as the width of the door-opening, so as to lie across the latter with its end resting on a ledge, e, when the door is closed, securely fastening the latter. When the door is to be opened, the loose end of the bar is turned up and the door slid to the position as shown in Fig. 2, a notch, x, in the frame receiving the end of the bar and preventing it from falling outward.

At the present time it is essential that box-cars be adapted to carry grain; also, that the grain boards or panels be readily placed and removed. Otherwise the services of a large number of men would be required, and, what is more important, much time would be lost. The ordinary straight panels, consisting of boards sawed off to fit the doors, are apt to be lost or stolen, being light, easily removed, and readily cut up. It has been attempted to avoid these losses by forming each grain-door in one piece, of a heavy frame and panels, and sliding in grooves vertically and horizontally, so as to be undetachable; but such a door is heavy, difficult to move when the grain presses against it, and even when the car is empty requires the services of several men to change its position. To avoid these difficulties I use a number of panels, F F, consisting each of a light, plain strip or board, and I provide the door with side guides, f f', in which the panels may slide vertically, and which sustain them in place when arranged for holding a car-load of grain. The inside guide, f', is cut away near the top of the car to leave a passage, w, wide enough to slide one of the panels laterally until it is moved from between the guides f f' into the space between vertical guides f' f'', when it can slide downward until it rests on stops y. To prevent the removal of the panel when it is being slid laterally, guides i are so arranged above the opening w that the panel must occupy a position between them before and as it is moved into the said opening. As each panel is light

and narrow, it can be readily moved by one man without danger of jamming, and even when the grain presses against the same.

It will further be evident that a door made of a number of plain boards is not only cheaper than one made of a heavy frame and panels bolted therein, but is also more readily replaced in case of breakage, which is very apt to occur from various causes.

10 I claim—

1. The combination, in a box-car, of the end door, bar *b*, pivoted to the inside of said end door, near the outer edge, and frame having a rest, *e*, and notch *x*, substantially as set forth.

2. The combination, in a box-car, of a grain-door consisting of separate loose panels *F* and two sets of vertical guides, a passage between them adapted to receive the panels separately, and guides *i* above said passage, substantially as set forth. 15

In testimony whereof I have signed my name to this specification in the presence of two subscribing witnesses. 20

B. FRANK TEAL.
